CLAIM

The ornamental design for a case for watches, as shown and described.

DESCRIPTION

The patent or application file contains at least one drawing executed in color. Copies of this patent or patent application publication with color drawing(s) will be provided by the Office upon request and payment of the necessary fee.

2. Case for watches

2.1 : Front

2.2 : Perspective

2.3 : Perspective

2.4 : Perspective

2.5 : Perspective

The design concerns a case for watches having different states, in which different periodic elements are visualized.
